CLAIM

The ornamental design for a timing device, shown and described.

DESCRIPTION

FIG. 1 is a front perspective view of the timing device (showing a stethoscope in phantom), in accordance with my invention;

FIG. 2 is a front elevational view thereof;

FIG. 3 is a right side elevational view (the left side being a mirror image thereof);

FIG. 4 is a top plan view thereof;

FIG. 5 is a bottom plan view thereof; and,

FIG. 6 is a rear elevational view thereof.

The broken line showing of clips and a stethoscope is for illustrative purposes only and forms no part of the claimed design.
